UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

COMPRESSOR-UNLOADING MEANS.

Application filed February 25, 1924. Serial No. 694,926.

My invention relates to compressor unloading means.

An object of my invention is to provide an improved compressor unloading means, and 5 more especially an improved compressor unloading means of the auxiliary unloader type. It will be understood that unloading means of this type are adapted to be used with a compressor having an intake type unloader; 10 and have for their particular function the avoiding of excessive temperatures due to the compression of any air which might leak past the intake unloader valve when the compressor is turning over unloaded from a partial 15 vacuum to receiver pressure. Other objects and advantages of my invention will be apparent in the course of the following specification and appended claims.

In the accompanying drawings I have shown 20 for purposes of illustration several embodiments which my invention may assume in practice.

In these drawings,—

Fig. 1 is a sectional view through one illustrative embodiment of my improved unloading mechanism.

Fig. 2 is a similar section on the line 2—2 of Fig. 1.

Fig. 3 is an end view of this mechanism.

Fig. 4 is a sectional view through a different illustrative form on a plane corresponding to the line 4—4 of Fig. 6, parts being shown in elevation.

Fig. 5 is a section on the line 5—5 of Fig. 6.

Fig. 6 is an end view with a portion cut away to show details of the construction of this second illustrative form of my invention.

Fig. 7 is a view corresponding to Fig. 4 through a third form.

As the details of construction of compressors with which mechanism of this type may be used are so well known, it seems unnecessary to illustrate one of these mechanisms in position upon a compressor. The general disposition of these devices may, however, be observed if necessary in the patent to H. C. Johansen, 1,404,176, patented Jan. 17, 1922. Compressors of the type with which this mechanism is used comprise low and high pressure cylinders connected by an inter-cooler, and the low pressure cylinder intake is controlled by an intake closure valve. As a result, when the compressor is unloaded, if the valve does not seat perfectly tight, there is some small leakage of air into the low pres-

sure cylinder; but this is not of sufficient quantity to maintain the inter-cooler pressure as high as atmospheric pressure, for the high pressure cylinder keeps this pumped down to quite a substantial vacuum despite the 60 leakage. As a result, what little air does leak in must be compressed in the high pressure cylinder from a partial vacuum up to receiver pressure; and there is thereby produced a very high temperature on account of the number of compressions, with resultant burning of the lubricant, damage to valves and other injurious consequences. For the purpose of avoiding the compression of any air which may leak in, and to vent it to the atmosphere 70 whenever the pressure exceeds atmospheric, I have devised the invention, three illustrative forms of which are shown herein.

As a preliminary it may be stated that these three forms differ from each other primarily 75 in that use has been made of three different types of valve mechanism, namely, the end seating or poppet type, the slide type, and the piston type, in the three forms. Taking up the first form which is shown in Figs. 1, 2 and 80 3, it will be observed that it comprises a casting 1 from whose opposite sides pipes 2 and 3 lead to the counterbores or clearances at the opposite ends of a high pressure cylinder of a compressor. The pipes 2 and 3 open into 85 chambers 4 and 5 respectively which are arranged at opposite sides of a chamber 6 which opens into a larger chamber 7. Chamber 7 is in turn connected by a series of ports 8 controlled by a thin annular valve 9 with a recess 90 10 formed in a cap member 11, there being an opening 12 leading to the atmosphere through the cap member 11. A spring 13 transversely flexed and held in position by a machine screw 14 serves to maintain the valve 9 normally seated but permits it to open when the pressure within the chamber 7 is substantially above atmospheric pressure. Between the chambers 4 and 5 and the chamber 6, there are arranged a pair of valve seats 15 and 16 respectively, these being coaxial with each other. Valve means including a pair of coaxially arranged valves 17 and 18 connected by a stem portion 19 and mounted upon the upper end of a piston 20 are adapted to seat 100 upon the seats 15 and 16 and interrupt communication between lines 2 and 3 and the chamber 6. It will be observed that the piston 20 is reciprocable in a cylinder 21, that it is normally held in the position shown in 110

Fig. 1 by a spring 22 whose tension may be adjusted by the adjustment of follower 23 by means of an adjusting screw 24, and that during the compressing operation of the compressor it will also be held in the position shown by intercooler pressure conducted through a pipe 25 which communicates with the space below the piston 20.

From the description that has been given 10 the mode of operation of this mechanism will be at once readily apparent. When the compressor is running loaded the pressure in the intercooler will be substantially above atmospheric, probably approximately one-half the 15 desired pressure to which the high pressure cylinder compresses the fluid pumped. Accordingly, at this time the piston 20 will be held up both by the intercooler pressure and by the pressure of the spring 22; and the maximum 20 pressure communicated from the high pressure cylinder acting upon the much smaller effective area of valve 17 exposed thereto will be insufficient to open the valves. When, however, the compressor is unloaded and the intake closure valve operates to discontinue 25 the admission of fluid to the compressor intake, the intercooler pressure will rapidly fall to less than atmospheric and accordingly the piston 20 will be moved downwardly; and the two 30 ends of the cylinder will then be connected to each other through the chamber 6; and when the pressure in the cylinder exceeds atmospheric pressure it will force the valve 9 off its seat and pass to the atmosphere through the passage 12. When the compressor is re-loaded and as soon as the intercooler pressure 35 builds up to the necessary degree, the valves 18 and 17 will seat and the compressor will operate in a normal manner. It should be noted that a counterbore 26 is provided at the upper end of the bore 21 and if this is connected by a small port 26' to the atmosphere the opening of the valves will be more positive and continuous during unloaded running.

In the form of my invention shown in Figs. 4, 5, and 6, instead of using a pair of end seating valves to control communication between the pipes 2 and 3, and between them and the atmosphere, I have provided slide valve 40 mechanism for accomplishing this same function. Herein it will be noted that the parts 20, 21, 22, 23, and 24, 25 and 26, are to all intents and purposes identical with those previously described and referred to by these same numbers, but instead of employing the poppet valves a pair of slide valves 31 and 32 are provided. These valves are reciprocable in chambers 33 and 34 respectively communicating with the pipes 2 and 3 and opening through ports 35 and 36 into a recess 37 corresponding to the recess 8. A suitable valve 39 and spring 40 are provided for controlling the venting of fluid to the atmosphere; and a suitable atmospheric vent 41 corresponding to the vent 12 may further be provided. It will

be noted that the ports 35 and 36 open through a flat valve seat surface 42 and that the valves have flat faces 43 and 44 cooperating with these seats. The valves are held in position by parallel lugs 45 seating in cut away portions 46 on a stem 47 projecting upwardly from the piston 20, and springs 48 lodged in recesses 49 within the stem maintain these valves seated. As the mode of operation is precisely like that previously described except that upon unloading the valves move downwardly and uncover the passages 35 and 36 by sliding off them, no further description of this form of my invention seems necessary.

In Fig. 7 a still further and more pronouncedly modified construction is presented. In this case the pipes 2 and 3 leading to the counterbores at the opposite ends of the cylinder open into annular grooves 52 and 53 formed in the inner walls of a cylindrically bored housing 54. Within the bore 55 of this housing a piston 56 is reciprocable and this piston is normally maintained in the position shown in Fig. 7 by a spring 58 which cooperates with an adjustable follower 59 at its lower end. This follower is adjusted by a screw 60 in a manner similar to the adjustments of the previously described springs. A connection 61 leads off to the intercooler from the space within the bore 55 at the lower side of the piston 56. At its upper side the piston 56 carries an upwardly extending boss 62 which at its extreme upper end is provided with an enlarged portion providing a valve seating surface 63 upon which an annular valve 64 is normally held seated by a resilient bowed spring 65 held in position by a screw 66. A cover 67 threaded as at 68 to the top of the casing member 54 encloses the valve mechanism and provides a shoulder 69 against which the outermost portion of the valve seat is adapted to rest. An atmospheric vent is shown at 70 from the chamber 71 in which the valve is mounted. The space between the enlarged portion carrying the valve seat 63 and the portion 56 is sufficient to connect the grooves 52 and 53 when the parts have moved to bottom position.

In the operation of this mechanism it will be evident that when intercooler pressure falls below atmospheric pressure to the requisite degree, the piston 56 and all the connected parts will move downward, and that the piston, having moved downward, will uncover the annular grooves 52 and 53 and they will be freely in communication with each other through the space surrounding the boss 62. As the piston moves downward its valve seat portion will also move downward in a like manner and as a result there will occur a separation between the valve seat and the shoulder 69. Any pressure admitted to the space surrounding the boss will, however, be without influence upon the movement of the piston; and any excess pressure suffi-

cient to overcome the pressure of the spring 65 will unseat the valve 64 and be vented to the atmosphere. On reloading, the parts will move up to the position shown in Fig. 7 again.

5 It will be evident that in all forms of my invention which I have illustrated herein there will be an automatic avoidance of any harmful temperatures, and that the opposite ends of the cylinder will be brought into communication with each other before the pressure in the intake to the high pressure cylinder is lowered to any substantial extent below atmospheric pressure. It is furthermore evident that simultaneously with the opening of 10 communication between the ends of the cylinder, an outlet to the atmosphere is provided for the fluid as fast as it reaches a little above atmospheric pressure.

While I have in this application specifically 20 described several embodiments which my invention may assume in practice, it will be understood that these forms of the same are shown for purposes of illustration and that the invention may be modified and embodied 25 in various other forms without departing from its spirit or the scope of the appended claims.

What I claim as new and desire to secure by Letters Patent is:

30 1. In an unloading mechanism, in combination, a casing having chambers respectively communicating with the opposite ends of a compressor cylinder, an intermediate chamber communicating with the atmosphere, valve means operative to connect said first mentioned chambers with said intermediate chamber and through the latter with each other, and means directly responsive to intercooler pressure for controlling the position of 35 said valve means.

2. In an unloading mechanism, in combination, a casing having chambers respectively communicating with the opposite ends of a compressor cylinder, an intermediate chamber communicating with the atmosphere, end seating valve means operative to connect said first mentioned chambers with said intermediate chamber and through the latter with each other, and means directly responsive to 45 intercooler pressure for controlling the position of said valve means.

3. In an unloading mechanism, a casing having chambers respectively communicating with the opposite ends of a compressor cylinder, an intermediate chamber communicating with the atmosphere, end seating simultaneously movable valve means operative to connect said first mentioned chambers with said intermediate chamber and through the latter with each other, and intercooler pressure responsive means for controlling the position of 50 said valve means.

60 4. In an unloading mechanism, a casing having chambers respectively communicating with the opposite ends of a compressor

cylinder, an intermediate chamber communicating with the atmosphere, end seating valve means simultaneously movable in the same directions and operative to connect said first mentioned chambers with said intermediate chamber and through the latter with each other, and intercooler pressure responsive means for controlling the position of said valve means.

5. In an unloading mechanism, a casing 75 having chambers respectively communicating with the opposite ends of a compressor cylinder, an intermediate chamber communicable with the atmosphere, spring loaded valve means controlling said communication, 80 valve means operative to connect said first mentioned chambers with said intermediate chamber and through the latter with each other, and intercooler pressure responsive means for controlling the position of said valve means.

6. In an unloading mechanism, a casing having chambers respectively communicating with the opposite ends of a compressor cylinder, an intermediate chamber communicable with the atmosphere, spring loaded valve means controlling said communication, 90 end seating valve means operative to connect said first mentioned chambers with said intermediate chamber and through the latter with each other, and intercooler pressure responsive means for controlling the position of said valve means.

7. In an unloading mechanism, a casing 100 having chambers respectively communicating with the opposite ends of a compressor cylinder, an intermediate chamber communicable with the atmosphere, spring loaded valve means controlling said communication, end seating simultaneously movable valve 105 means operative to connect said first mentioned chambers with said intermediate chamber and through the latter with each other, and intercooler pressure responsive means for controlling the position of said valve means.

8. In an unloading mechanism, a casing having chambers respectively communicating with the opposite ends of a compressor cylinder, an intermediate chamber communicable with the atmosphere, spring loaded valve means controlling said communication, end seating valve means simultaneously movable in the same directions and operative to connect said first mentioned chambers with said intermediate chamber and through the latter with each other, and intercooler pressure responsive means for controlling the position of 115 said valve means.

9. In an unloading mechanism, means 125 forming a pair of chambers respectively communicating with the opposite ends of a high pressure cylinder, each of said chambers being further provided with a port adapted to connect the same to the atmos- 130

- phere, valve means respectively controlling said atmospheric ports, and a single actuating means directly controlled by intercooler pressure for moving both said valve means 5 relative to said ports.
10. In an unloading mechanism, means forming a pair of chambers respectively communicating with the opposite ends of a high pressure cylinder, atmospheric vent means, 10 a pair of valve means respectively controlling communication of said chambers with said atmospheric vent means, and means including a single piston movable in accordance with pressure variations resulting from unloading 15 for simultaneously moving said valve means.
11. In an unloading mechanism, means forming a pair of chambers respectively communicating with the opposite ends of a high pressure cylinder, atmospheric vent means, 20 valve means respectively controlling communication of said chambers with said atmospheric vent means, and means including a single piston normally held in position to close said valve means and movable in accordance with pressure variations resulting 25 from unloading for simultaneously moving said valve means to open positions.
12. In an unloading mechanism, a casing having chambers respectively communicating 30 with the opposite ends of a compressor cylinder, atmospheric vent means, valve means controlling the intercommunication between said chambers and their communication with said atmospheric vent means, and common 35 means controlled by pressure variations resulting from unloading for controlling the position of said valve means and operative to effect such intercommunication between said chambers.
- 40 13. In an unloading mechanism for the high pressure cylinder of a compound compressor, a casing having chambers respectively communicating with the opposite ends of a compressor cylinder, atmospheric vent 45 means, and means movable in accordance with variations in pressure growing out of unloading the compressor for simultaneously providing access between said chambers and with said atmospheric vent means.
- 50 14. An unloading mechanism adapted for connection to a compressor cylinder comprising multi-valve means movable as a unit to effect an unloading controlling function simultaneously with respect to the two ends 55 of a compressor cylinder, and vacuum controlled means for effecting the movement of said valve means.
15. An unloading mechanism adapted for connection to a compressor cylinder comprising means forming fluid conducting passages 60 adapted to communicate respectively with the ends of a compressor cylinder, valve means individual to each passage for controlling flow of fluid from the compressor to the atmosphere by way of said passages, common 65 means for always maintaining said valve means in an open position while the compressor is unloaded to permit fluid in said compressor to be discharged to the atmosphere, and one-way flow control means for 70 preventing back flow of fluid to said compressor.
16. An unloading mechanism adapted for connection to a compressor cylinder comprising means forming fluid conducting passages adapted to communicate respectively with the ends of a compressor cylinder, valve means for interconnecting said passages and for connecting the same to atmosphere whereby the ends of the compressor cylinder may be 75 placed in communication with each other and the fluid in the compressor discharged to the atmosphere, and one-way flow control means for preventing back flow of fluid to said compressor.
17. An unloading mechanism adapted for connection to a compressor cylinder comprising a casing provided with chambers adapted for connection respectively with the ends of a compressor cylinder, means comprising a unitary valve mechanism for interconnecting said chambers and connecting the same to atmosphere whereby an unloading function with respect to both ends of the cylinder is effected simultaneously, and intercooler pressure responsive means for controlling said unitary valve mechanism.
18. An unloading mechanism adapted for connection to a compressor cylinder operative to effect unloading by venting and to allow 100 communication between the ends of a compressor cylinder including passage forming means adapted for connection to the opposite ends of a cylinder, and a unitary valve mechanism for controlling intercommunication 105 between said passage forming means and effecting unloading by venting.
19. An unloading mechanism adapted for connection to a compressor cylinder comprising valve means movable as a unit to interconnect the ends of a compressor cylinder, and means controlled by cylinder intake pressure controlling said valve means.

In testimony whereof I affix my signature.

HALBERT B. HALVORSEN.

CERTIFICATE OF CORRECTION.

Patent No. 1,708,171.

Granted April 9, 1929, to

HALBERT B. HALVORSEN.

It is hereby certified that error appears in the printed specification of the above numbered patent requiring correction as follows: Page 4, line 101, claim 18, for the word "communication" read "intercommunication", and line 105, for the word "intercommunication" read "communication"; and that the said Letters Patent should be read with these corrections therein that the same may conform to the record of the case in the Patent Office.

Signed and sealed this 7th day of May, A. D. 1929.

M. J. Moore,
Acting Commissioner of Patents.
